Conn., a corporation of Delaware

Application December 31, 1943, Serial No. 516,355

8 Claims. (Cl. 86—1.5)

The present invention relates, in general, to ammunition manufacture, and, in particular, to an improved machine for separating or pulling down cartridges into their component parts.

The embodiment of the invention shown and described herein is exemplary of a device especially suited for withdrawing bullets from the mouths of cartridge cases, but it will be understood that modifications of the specific structure illustrated and described may be made and are included within the scope of the appended claims.

In the manufacture of small arms ammunition, and, in particular, .30 and .50 caliber ball and armor piercing cartridges, a certain percentage of the finished cartridges inevitably fail on inspection to meet ordnance specifications, and hence are rejected. To reduce the loss represented by these rejects, it is the practice of manufacturers to pull down or reclaim all acceptable components of the cartridges and to use these reclaimed components over again.

Various devices have been used to remove the bullets from cartridge cases, but these earlier devices have been unsuccessful in that the bullets were scratched or deeply scarred by the bullet engaging jaws of the pull down machine.

An object of the present invention is to pull down cartridges without scratching or marring the cartridge components. A further object is to provide an improved machine for withdrawing bullets from the mouths of cartridge cases. A still further object is to provide a fluid operated chuck for gripping a bullet and drawing it out of a cartridge case without defacing or scratching the surface of the bullet.

These and other objects, features and advantages of the invention will be described in more detail in the following specification which is descriptive of the exemplary embodiment of the invention illustrated in the accompanying drawings, in which:

Fig. 1 is a front elevation of a machine adapted to embody the cartridge pull down device of this invention.

Fig. 2 is a right side elevation of the fluid operated chuck of this invention showing the fixed stops of the machine frame.

Fig. 3 is a left side elevation of the chuck of Fig. 2.

Fig. 4 is a plan view of the chuck and the fluid operating means therefor on lines 4—4 of Fig. 3.

Fig. 5 is a side elevation in section on line 5—5 of Fig. 4, including a fragmentary part of the cartridge feeding and supporting means.

Fig. 6 is a perspective view of one of the segments of the split sleeve chuck.

Referring to the drawings, Fig. 1 shows a machine which is especially suited for actuating the cartridge pull down device of this invention and comprises a base 10 having a cartridge supporting plate 11 on which is rotatably mounted a dial 12 provided with a plurality of circumferentially spaced apertures 13, see Fig. 5, adapted to retain the cartridges substantially upright on the supporting plate 11. The dial 12 is provided with ratchet teeth 14 around its periphery adapted to be engaged by an actuating pawl 15 which rotates the dial 12 intermittently thereby sliding or feeding the cartridges over the surface of the plate 11 to the operating station of the machine hereinafter described.

Mounted substantially vertically on the base 10 are a pair of spaced substantially parallel frame members 16 on the upper ends of which is mounted a crankshaft, indicated generally at 17. The latter is provided at one end with a fly wheel 18 which is driven from a power source (not shown). The opposite end of the crankshaft 25 carries a disk 19 having an eccentric pin 23 thereon to which is connected the upper end of a connector 22 pivoted at 22' to the frame member 16. The lower end of the connector 22 is pivoted at 7 to a horizontally disposed link 8 which in turn is pivoted at its rear end to a slide block 9 movable in ways 9' fixed to the frame 16. The pawl 15 is pivotally carried on the front end of the slide block 9. For each revolution of the crankshaft, the cartridge feeding dial 12 is rotated so as to move a cartridge step-by-step to the operating station and remove a pulled down cartridge case from the operating station. The pulled down case will subsequently be moved by the dial 12 over an aperture in the plate 11 and be automatically discharged from the machine. As each cartridge case is moved into position at the operating station, it is temporarily clamped to the supporting plate 11 by means of a short section of flanged track 23, the flanges of which are adapted to engage in the extraction groove of a case head. Thus, a considerable upward force may be exerted on the bullet to pull the bullet out of the case, the latter being securely held in its aperture in the feed dial 12.

Rotatably supported on the crankshaft 17 is a connecting rod 24 having a gate 25 at its lower end constructed and arranged to reciprocate in substantially vertical ways 26 secured to the legs 16 of the machine. The gate 25 is a rela-

tively heavy substantially rectangular block provided with a forwardly projecting substantially semicircular ring 27 welded or otherwise secured on the front face thereof. A relatively heavy coil spring 28 is shown secured at its lower end to the gate and at its upper end to a fixed part of the frame to compensate for the additional weight of the fluid operated chuck which is adapted to be secured thereto as hereinafter described and to facilitate restoration of the gate to its upper position. The gate 25 defines the operating station of the machine.

The description thus far has been a brief disclosure of the essential elements of a well known type of machine for manufacturing cartridges and is described in greater detail in Patent No. 605,340, W. B. Place, June 7, 1898.

The fluid operated chuck of this invention is shown in detail in Figs. 2 through 6 and comprises a chuck supporting block 30 which is substantially rectangular in cross section and which, for simplicity of construction, may be made in two parts 30' and 30" secured together by bolts 32, as shown in Fig. 2. The block 30 is provided with a substantially rectangular slot 33 which is open at the underside of the block 30 and extends transversely across the forward end thereof. A substantially vertical hole 34 is shown drilled or bored down through the forward end of the block 30 from the top surface thereof into the rectangular slot 33, the vertical axis of the hole intersecting the longitudinal axis of the block 30 and lying in a vertical plane on the longitudinal axis of the slot 33. The diameter of the hole 34 is substantially equal to the width of the rectangular slot 33, whereby the intersecting walls of the slot and drilled hole are substantially flush. A counterbore 35 of suitable depth is formed in the upper end of the hole 34 and provides a square shoulder or seat 36 for supporting a chuck hereinafter described.

A substantially rectangular slot 38 of relatively shallow depth is milled or otherwise formed transversely across the top face of the block 30, the longitudinal axis of the slot 38 being parallel to and in substantially the vertical plane of the longitudinal axis of the lower slot 33. The bottom surface of the slot 38 defines shoulders 39 at the upper edge of the counterbore 35.

The shoulders 39 are adapted to support a cylindrical throat member 40 which is provided with a substantially rectangular flange 42 on its lower end adapted to fit in the slot 38 and to be secured therein by suitable countersunk bolts 43, see Figs. 4 and 5, which are threaded into the shoulders 39 of the slot 38. The throat member 40 is cored axially as at 44, the lower edge of the axial aperture 44 having bevelled edges 45. The upper end of the aperture 44 is counterbored as at 46 to provide shoulders 47 to support the lower end of a bullet discharge chute 48 which, as shown in Fig. 1, is provided with a laterally extending funnel 49 adapted to discharge the extracted bullets from the machine, as herein-after described. A substantially rectangular recess 50 is shown in the forward face of the throat member 40, the bottom 52 of the recess comprising a vertically inclined plane surface sloping outwardly, as shown in Fig. 5.

The fluid operated chuck is indicated generally 70 at 53 and comprises a cylindrical split sleeve consisting of two substantially semicylindrical parts or segments 53' and 53" adapted to be floatingly supported in the bore 34 of the block 30. Each part or segment is provided with a semicircular

flange 54' and 54" respectively on its upper edge adapted to seat freely on a corresponding shoulder 36 of the counterbore 35. The respective semicylindrical bores 55' and 55" of each sleeve 53 segment is substantially equal in diameter to the diameter of a cartridge bullet and is nicely finished to present a smooth polished surface to a bullet, the latter being adapted to be gripped tightly between the cooperating surfaces 55' and 55" as hereinafter described. Each bore of the cylindrical segments is also provided with a relatively long counterbored portion 56' and 56" respectively in the upper end thereof of such diameter that a bullet in this portion of the bore of the chuck will be loosely supported therein; and a relatively short counterbored portion 57' and 57" in the lower end thereof, the diameter of the latter being substantially equal to the outside diameter of the neck portion of a cartridge case so that the upper end or mouth of the case will be properly guided within the cooperating counterbores 57' and 57" when the chuck 53 is lowered into engagement with the bullet. The lower end of each sleeve segment is suitably tapered as shown in 58' and 58" respectively to provide clearance for the shoulder of the cartridge case.

Each sleeve segment is provided with a pair of semispherical recesses 59, see Fig. 6, located on opposite sides of the counterbore portions 56' and 56" respectively of each sleeve and adjacent the upper end thereof.

In assembling the two semicylindrical segments within the bore 34 of the block 30, a steel ball 60 is mounted in each pair of cooperating recesses 59 of the segments, the recesses being of a depth such that the cylindrical segments are held spaced apart slightly by the balls 60 as shown in Fig. 5. As pointed out above, the flanges 54' and 54" of the respective segments are adapted to be freely mounted on corresponding shoulders 36 of the bore 34. To this end, the bevelled surfaces 45 are provided on the lower end of the funnel 40, and the counterbore 35 is of such depth that the flanges of the respective segments of the chuck 53 fit loosely between the surfaces 45 and the shoulders 36 of the counterbore, and hence are enabled to move independently of each other, the parts pivoting slightly about the balls 60 as fulcrum points.

Mounted in a horizontally disposed hole 62, which is drilled and tapped in the front face of the block 30 and which intersects the hole 34 of the block 30 is a ball 63 which is backed by a suitable coil spring 64 held in place by a screw 65 threadedly secured in the hole 62 and adapted to vary the compression force of the spring 64.

In accordance with this construction, the front sleeve segment 53" is engaged by the spring pressed ball 63 and constantly urged to pivot clockwise, see Fig. 5, about the fulcrum ball 60 and thus normally to bring the two sleeve segments together to provide an axial bore of minimum diameter. Consequently, whenever a bullet is thrust up into the resilient jaws or segments of the chuck, it will be retained therein following its extraction or withdrawal from the mouth of a cartridge case. It will be clear, however, that the restraining force of the spring pressed ball 63 is inadequate for imparting sufficient gripping force to the jaws to effect extraction.

The gripping force necessary for carrying out the pull down or extraction operation is provided by suitable fluid operated means for moving the jaws of the chuck together. The term "fluid," as

used herein, shall be understood to designate both liquid and gaseous mediums. In the embodiment shown herein, air is the fluid used but it will be understood that hydraulically operated means are included within the scope of the appended claims. Referring to Figs. 3 and 4, the chuck operating means comprises a pneumatically operated cam or eccentric disk 66 carried on a shaft 67 which is rotatably mounted in horizontal bearings in the block 30. The eccentric disk 66 is located within a pocket 68 which is formed in the block 30 by milling out circular recesses in adjacent faces of the disassembled blocks 30' and 30'', see Fig. 4, and is of sufficient diameter to enable the cam or eccentric disk 66 to have suitable clearance therein, as shown in Fig. 5.

The forward edge of the pocket 68 intersects the wall of the bore 34 of the block 30 to provide an opening into the bore 34. The shaft 67 is supported in its bearings which are so located with respect to the bore 34 that the eccentric periphery of the cam 66 normally lies outside of the bore 34 but is enabled on rotation of the shaft 67 to project into the bore 34 so as to engage with the adjacent surface or wall of the sleeve segment 63'. One end of the shaft 67 is extended beyond the side of the block 30 to provide a hub 67' to which a cam operating lever, indicated generally at 69, is securely fastened. The lever 69 comprises an apertured head portion 69' adapted to be keyed or otherwise secured to the hub 67' and is provided with a rearwardly extending cylindrical rod 72, the latter being slidable within a cylindrical sleeve 73 which is bifurcated at its rear end 73' to receive an apertured tongue 74 of a sleeve connecting link 75. Suitable means such as a pin 76 is provided for pivotally securing the tongue 74 between the bifurcations 73' of the sleeve 73.

The connecting link 75 is shown fastened securely by a bolt or pin 77 to the lower end of a piston rod 78 which carries a piston 79 on its upper end, see Fig. 4, reciprocable within an air cylinder 80. The latter is a well known type of cylinder having a valve box 82 on one side thereof provided with a vertically sliding valve operating rod 83 and suitable inlet and exhaust port connections, indicated generally at 84.

The cylinder 80 is bolted securely in a substantially vertical position on a horizontally disposed shelf 85 which is secured at its forward end by bolts 86 to the top surface of the block 30 adjacent the rear end thereof. The rear end of the shelf 85 is bifurcated, as indicated by the dotted lines 87 in Fig. 4, to provide clearance for the piston rod 78 and is supported by a diagonally arranged brace 88, the upper end of which is fastened by a weld joint to one side of the plate 85, the lower end of the brace being secured by one of the bolts 32 to the adjacent side of the block 30.

The lower end of the valve operating rod is threaded and provided with a pair of vertically spaced adjusting nuts 89 having flanged collets 90, the flanges of which constitute bearing surfaces for articulately connecting the lower end of the valve rod to one end of a valve rod actuating lever arm 92. The latter is pivotally supported intermediate its ends by a bolt 93 which is secured in the outer end of a frame member 94 suitably fastened at its forward end to the rear end of the block 30. The rear end of the lever arm 92 is adapted to be located in the vertical plane of a pair of vertically spaced fixed stops 95 which are adjustably secured in drilled and

tapped bosses 96 welded or otherwise formed on the inside surface of one of the upstanding legs 16 of the machine, as shown in Fig. 1.

The block 30 including its assembled chuck and pneumatically operated chuck actuating means is adapted to be detachably secured to the reciprocating gate 25 of the machine by inserting the upper end of the throat 40 through the ring 27 of the gate. A suitable screw or bolt 97 is shown threadedly engaged in the tapped hole in the ring 27 and is adapted to be turned up until its inner end engages the inclined surface 52 of the recess 50 in the throat 40. In this manner, the entire chuck assembly is fastened to the gate and is reciprocated thereby whereby the rearwardly extending end of the lever arm 92 is moved into and from engagement with the respective stops 95.

The operation of the machine is as follows: Cartridges are loaded into the apertures 13 of the feed dial 12 which traverses the cartridges step-by-step to the operating station identified by the reciprocating gate 27. The heads of the cartridges are supported and slide on the plate 11 while being moved to the operating station and in the latter position the extraction grooves of the cartridge heads are engaged by the flanged guide tracks 23. The cartridge case is thus temporarily held down on the plate 11 at the operating station, thus enabling an upward force applied to the bullet to separate the bullet from the case. As the downwardly moving gate approaches the bottom of its stroke, the chuck 53 is forced down over the bullet. As described above, the jaws of the chuck are normally closed, the jaw segment 53'' being held in a rearwardly displaced position by the spring pressed ball 63, but are enabled to spread apart as the chuck moves down over the bullet.

In its lowermost position, the counterbores 57' and 57'' of the chuck engage the neck of the cartridge case so as to align the case axially with the bore of the chuck. Simultaneously, the rear end of the lever arm 92 engages the lower fixed stop 95 of the frame and is pivoted counterclockwise, see Fig. 2, whereupon the valve operating rod 83 is actuated to admit air under pressure into the air cylinder 80 so as to force the piston 79 up. The cam operating lever 69 is thereby pivoted upwardly, see Fig. 3, rotating the cam 66 clockwise so that a portion of its eccentric periphery represented by the dotted lines enters into the bore 34 engaging the adjacent surface of the pivotally mounted jaw segment 53' and forcing the latter to pivot counterclockwise slightly. The bullet and jaw segment 53'' are thereupon shifted in a similar direction or forwardly in the bore 34 bringing the sleeve segment 53'' hard up against the forward wall of the bore 34 and compressing the coil spring 64. The bullet is thus clamped firmly between the smooth substantially cylindrical surfaces 55' and 55'' of the respective chuck jaws and is thereupon pulled or drawn out of the mouth of the case as the gate moves upwardly. At the top of the stroke, the rear end of the lever arm 92 engages the upper fixed stop 95 whereupon the lever arm is pivoted clockwise, see Fig. 2, setting the valve operating rod 83 so that air is admitted into the cylinder 80 to drive the piston down. The cam operating rod 69 is thereupon moved downwardly, see dotted lines in Fig. 3, rotating the cam 66 counterclockwise and withdrawing its eccentric periphery from engagement with the adjacent

surface of the jaw segment 53'. The bullet is thereupon released from the firm grip of the pneumatically closed jaws but is simultaneously held in the jaws of the clamping action of the spring pressed jaw segment 53" which takes effect immediately following release of the jaw segments by the pneumatically operated eccentric cam. Thus, when the gate again moves down, the base of the extracted bullet, which is retained in the chuck jaws, is engaged by the nose of the bullet of the next succeeding cartridge to be pulled down. The first or extracted bullet is thereupon pushed upwardly in the chuck and is loosely supported by the entering bullet in the counterbore portion 56' and 56" of the chuck. As the pull down operation proceeds, the extracted bullets are moved further up in the throat 44 and into the discharge chute 48 from which they are discharged by the funnel 49 into a suitable tote box or other container (not shown). The pulled down cartridge cases are automatically discharged from the machine at a station succeeding the operating station by dropping through an aperture of the supporting plate 11.

The pulling down or separation of the cartridge components is thus continuous as long as cartridges are supplied to the feed dial 12. Moreover, the bullets which are removed from the cases are free from scratches or disfigurations of any kind, and hence are reclaimable for subsequent use.

What is claimed is:

1. A machine for separating components of an article comprising article supporting means; means for feeding articles on said supporting means to an operating station; a chuck at said station; fluid operated means to positively close said chuck, said chuck having a smooth cylindrical bore when closed to grip one component of said article; means to move said chuck relative to said supporting means to separate the component in said chuck from other components of said article, said fluid operated means being adapted thereafter to enable said chuck to open; and a spring associated with said chuck to resiliently hold the chuck closed thereby to retain the separated component in said chuck.

2. A machine for separating components of an article comprising article supporting means; means for feeding articles on said supporting means to an operating station; a reciprocating gate at said operating station; a fluid operated chuck carried by said reciprocating gate; valve means at one end of the stroke of said reciprocating gate to close said chuck, said chuck having a smooth cylindrical bore when closed to grip a component of said article whereby said component is separated from said article by relative movement of said gate and supporting means, said valve being actuated at the opposite end of the stroke to enable said chuck to open and thereby to release said component; and resilient means to hold the chuck in gripping engagement with said separated component.

3. In a cartridge pull-down machine, cartridge feeding means; means to actuate said feeding means to carry a cartridge to an operating station; cartridge hold down means at said operating station; a reciprocating gate at said operating station; a chuck carried by said reciprocating gate comprising jaws having smooth surfaces for gripping a bullet and withdrawing the bullet from a cartridge at said station by relative movement of said gate and hold down means; and

means for actuating the jaws of said chuck comprising fluid operated members, fixed stops on said machine, and an element carried by said fluid operated members to engage said fixed stops at the upper and lower limits of the stroke of said reciprocating gate.

4. In a cartridge pull-down machine, cartridge feeding means; means to actuate said feeding means to carry a cartridge to an operating station; cartridge hold down means at said operating station; a reciprocating gate at said operating station; a fluid operated chuck carried by said reciprocating gate comprising jaws having smooth surfaces for gripping a bullet and withdrawing the bullet from a cartridge at said station by the relative movement of said gate and hold down means; and a ring on said gate having a lock bolt therein to detachably secure said fluid operated chuck to said gate.

5. In a cartridge pull-down machine, cartridge feeding means; means to actuate said feeding means to carry a cartridge to an operating station; cartridge hold down means at said operating station; a reciprocating gate at said operating station; a pneumatically operated chuck comprising floating jaws carried by said reciprocating gate and means for closing said jaws on a bullet for withdrawing a bullet from a cartridge at said station by the relative movement of said gate and hold down means, said jaw closing means comprising a cam and a member for rotating said cam into engagement with one of said jaws to move said jaws positively together at the bottom of the stroke of said gate, said cam being rotatable out of engagement with one of said jaws to enable said jaws to separate at the upper end of the stroke of said gate.

6. In a cartridge pull-down machine, cartridge feeding means; means to actuate said feeding means to carry a cartridge to an operating station; cartridge hold down means at said operating station; a reciprocating gate at said operating station; a pneumatically operated chuck comprising floating jaws carried by said reciprocating gate; means for closing said jaws on a bullet for withdrawing a bullet from a cartridge at said station by the relative movement of said gate and hold down means, said jaw closing means comprising a cam and a pneumatically operated member for rotating said cam into engagement with one of said jaws to close said jaws at the bottom of the stroke of said gate; and resilient means for maintaining said jaws closed at the upper end of the stroke of said gate to hold the extracted bullet in said jaws.

7. In a cartridge pull-down machine, cartridge feeding means; means to actuate said feeding means to carry a cartridge to an operating station; cartridge hold down means at said operating station; a reciprocating gate at said operating station; a pneumatically operated chuck carried by said reciprocating gate for gripping and withdrawing a bullet from a cartridge at said station by the relative movement of said gate and hold down means, said chuck comprising a split sleeve to engage said bullet and elements supported between the segments of said split sleeve to enable said segments to move freely relative to each other; means for closing the segments of said split sleeve comprising a cam and a pneumatically operated arm for rotating said cam into engagement with one only of said segments to move it positively relative to the second

segment of said sleeve, said cam being rotatable out of engagement with said first segment to enable said segments to separate at the upper limit of the stroke of said gate; and a spring pressed element in engagement with said second segment to resiliently hold said sleeve closed after disengagement of said first segment by said cam.

8. In a cartridge pull-down machine, cartridge feeding means; means to actuate said feeding means to carry a cartridge to an operating station; cartridge hold down means at said operating station; a vertically reciprocating gate at said operating station; a chuck carried by said reciprocating gate comprising a pair of floating jaws adapted to be closed to seize a bullet and to withdraw said bullet from a cartridge case at said station; pneumatically operated means

5 carried by said gate to actuate said chuck jaws comprising a rotatable jaw engaging cam, and air cylinder having a piston, members connecting said cam to said piston, stops fixed to said machine, and a valve arm carried by said air cylinder constructed and arranged to engage said fixed stops at the upper and lower limits of said stroke of said gate to effect displacement of said piston in said cylinder and thereby to rotate said cam into and from engagement respectively with one only of said jaws; and a tubular element supported at the upper end of said chuck to discharge the bullets withdrawn from the cartridge cases from said machine while maintaining continuous operation of said reciprocating gate and cartridge feeding means.

MARION L. SAPPENFIELD.
